2 SHEETS—SHEET 2.

UNITED STATES PATENT OFFICE.

THEODORE BIRKENMAIER, OF ST. LOUIS, MISSOURI.

CONTROLLING MECHANISM FOR LAUNDRY-MACHINES.

1,374,810.

Specification of Letters Patent. Patented Apr. 12, 1921.

Application filed June 25, 1917. Serial No. 176,901.

To all whom it may concern:

Be it known that I, THEODORE BIRKEN-
MAIER, a citizen of the United States, and
residing at St. Louis, Missouri, have in-
5 vented new and useful Improvements in
Controlling Mechanism for Laundry-Ma-
chines, of which the following is a specifica-
tion.

This invention relates to washing ma-
10 chines, and more particularly to mechanisms
for automatically controlling the period of
operation of such machines. This invention
is an improvement on the machine shown
and described in my Patent Number
15 1,312,431.

In the machine disclosed in the patent
referred to, automatic controlling mecha-
nism is provided, embodying mechanism
which operates after a predetermined laun-
20 drying operation to open the drain and
thereafter shift the reversing mechanism to
neutral position to stop the machine. In
order to control the mechanism in accord-
25 ance with the operation of the laundry-
ing mechanism, such as the drum of a laundry-
ing tub, the mechanism should, of course, be
driven from the drum shaft. Since, how-
ever, the drums of different machines op-
30 erate at different speeds and different laun-
dry machines have different trains of
mechanism, it is necessary that this timing
mechanism be accommodated to the partic-
ular laundrying mechanism, both in speed
35 and in mechanical arrangement.

One of the objects of this invention, there-
fore, is to provide controlling mechanism
having provisions for adjusting the relation
between the laundrying and controlling
mechanisms.

Another object is to improve the construc-
40 tion of the controlling mechanism, so as to
simplify its operation and cheapen its cost
of manufacture.

Another object is to provide novel sig-
45 naling mechanism which will signal to the
operator when the operation on a lot of
clothes in the machine nears completion.

Further objects will appear from the de-
tail description taken in connection with the
50 accompanying drawings, in which,

Figure 1 is an elevation partly in section
of a washing machine, showing the con-
trolling mechanism embodying this inven-
tion;

55 Fig. 2 is a plan of Fig. 1;

Fig. 3 is an end elevation;

Fig. 4 is an enlarged section on the line
4—4, Fig. 2;

Fig. 5 is a detail front elevation of Fig. 4;

Fig. 6 is an enlarged detail of Fig. 2, 60
showing the signaling mechanism;

Fig. 7 is an end elevation of Fig. 6; and,

Fig. 8 is a section on the line 8—8, Fig. 6.

Referring to the accompanying drawings,
it will be seen that the washing machine, 65
which is of the type in general use, com-
prises a cylindrical water and suds receiv-
ing tub 1, mounted on end supports 2, con-
taining a rotary washing drum adapted to
receive the clothes or fabrics, and sustained 70
for rotation in the tub by means of trun-
nions 4, journaled in the end walls of the
tub and in suitable bearings on the sup-
port 2.

A drive shaft 6 is sustained in suitable 75
bearings, and this drive shaft carries loose
pulleys 7 and 8, and an intermediate tight
pulley 9, all adapted to be engaged by a
pair of belts 10 and 11, one of which is
crossed, adapted to drive the pulley 9 alter- 80
nately in reverse directions. Mounted in
the casing 12 is a train of gears connect-
ing the main drive shaft 6 with the trunnions 4,
and comprising a pinion 13 on the drive 85
shaft 6, a gear 14 on the trunnion 4, and an
idler 15 meshing with the gears 13 and 14.
It will be understood that the main drive
shaft 6 extends across the machine, and that
there is a train of gears on each end. The 90
belt shifting mechanism, which is of usual
construction and fully described in the ap-
plication referred to, comprises a shifter
head 16, mounted on guides 17, sustained by
a bracket 18 on the tub, and suitably 95
connected by belt loops with the belts 10 and
11, as shown in Fig. 2. The rock shaft 19 is
mounted for endwise movement in the
bracket 18, and is connected at its other end
with the head 16. A cam head 20 is fixed 100
to the rock shaft 19, and is adapted to co-
operate with lugs 21, on the bracket 18, to
shift the belts in neutral position, and is pro-
vided at its forward edge with a recess
adapted to engage a pin on the shifting 105
lever 26, which is oscillated by suitable
mechanism connected with and driven from
the pulley 7. The rock shaft is provided
with an arm 22 connected with a shifter rod
23, which extends forwardly, and is actuated 110
by the controlling mechanism in a manner
hereinafter to be described.

Mounted on the tub is a bracket 30, hav-

ing a bearing lug 31, in which is pivoted an arm 32, having a spherical head 33, bearing against the end of the rod 23, and having a head screw 34, passing through a slot 35 in this rod. A spring 41 connected at one end to the arm 32, and at its other end to a lug 36, on the bracket 30, normally tends to move the arm 32 to the right, Fig. 4, and in a direction to rock the shaft 19 to 10 disconnect the cam head 20 from the shifter arm 26, and shift the shifting head 16 to neutral position. This arm is provided with a grip 37, for manual operation, and is provided with a toe 38, adapted for engagement 15 by a latch 39, pivoted on the bracket and normally moved in a counter clockwise direction by a spring 40.

An outlet pipe 45 is provided with a valve 46 on a rod 47, which is connected to one end 20 of a lever 48, pivoted intermediate its ends on a lug 49, formed on the bracket 30, while the other end of this lever is connected by a link 50, with one arm of a bell-crank lever 51, pivoted in a lug 52 on the bracket 30.

25 The bracket 30 is provided with standards 55 and 56, supporting a guide 57, and also a threaded shaft 58. A spring 54 mounted between a shoulder on shaft 58 and the standard 55, acts to frictionally retain this 30 shaft.

Mounted to slide on the guide 57 and the shaft 58 is a carriage 59 which, as shown in Figs. 4 and 5, is provided with threaded semi-circular jaws 60, adapted to engage the 35 screw thread on the shaft 58, these jaws being pivoted intermediate their ends, and having handles 61, between which is interposed a spring 62 tending to keep the jaws in engagement with the thread on the shaft. 40 When the handles or arms 61 are moved toward each other, the jaws 60 are separated, so as to release the shaft and permit setting of the carriage 59. The carriage is provided with a lug 63, screwed 45 therein, and adjustable, and this pin is adapted to engage the tail 64 of the latch 39, so as to release this latch from the arm 32. The carriage is, furthermore, adapted to engage the lug 66 on the bell- 50 crank lever 51, so as to raise the valve 46 from its seat, and open the drain. It will, of course, be understood that the weight of the rod 47 is sufficient to close the valve. The standards 55 and 56 have mounted 55 thereon, a scale 67, coöperating with a suitable indicator on the carriage 59.

Fixed to the shaft 58 is a ratchet 68, engaged by a pawl 69, on the arm 70, mounted to oscillate on the shaft 58, and having an 60 arm 71 provided with an adjustable slot 72, engaged by a block 73 on a link 74, connected at its lower end to the crank 75 on the trunnion 4. The link 74 is in sections, which are connected by a spring 76.

65 The carriage 59 has mounted thereon, a

casing 80, in which is mounted a dial 81, having a hand wheel 82, and coöperating with a pointer on the casing, as shown in Fig. 5. This dial has also fixed thereto, a ratchet 83, coöperating with a pawl 84, pivoted at 85 on the bracket 30. This pawl has a stop 86 bearing against the bracket, and is moved to the left, Fig. 5, by a spring 87. It will be seen by reference to Fig. 5, that when the carriage is moved to the left, the 75 ratchet will engage the pawl to rotate the dial to the extent of one tooth.

The bracket 30 has mounted thereon a bracket 89, provided with a slot 91, in which is adjustably clamped a support 92, carrying a bell 93, engaged by a striker 94, on an arm 95, pivoted on a bracket 90, extending from the case 80 and moved toward the bell by a spring 96. This arm 95 is engaged by a finger 97, mounted on an arm 98, 85 loosely mounted on the shaft 58. The spring 99 holds the finger 97 against the pin 100. A pin 101 connects the arm 98 with the arm 70.

The operation of the mechanism will be 90 obvious from the disclosure in the application referred to. After a lot of clothes has been placed in the machine, the carriage 59 is moved to a position with respect to the scale 67, corresponding to the time of the 95 laundrying operation. The arm 32 is now pulled forwardly, thereby causing the latch 59 to engage under the toe 38, and latch the arm in position with the cam head 20, thrown to a position to make the connection 100 with the shifting arm 26. The drum is now driven alternately in opposite directions by the driving mechanism, and the pawl and ratchet connection between the trunnion 4 and the actuator shaft 58 for 105 the timing mechanism, will rotate this shaft step by step, and thereby cause the carriage 59 to move slowly to the right, Fig. 1. When the carriage engages the lug 66, the valve 46 will be raised from its seat, thereby 110 opening the outlet and draining the tub. Thereafter, the pin 63 will engage the tail 64 of the latch 39, so as to release the arm 32 and cause the spring 41 to move the cam head 20 out of engagement with the shifter 115 arm, and into engagement with the lugs 21, so as to shift the belts to neutral. The connections between the carriage and the actuated devices are so constructed and proportioned that the tub outlet will be opened a 120 sufficient length of time prior to the stopping of the mechanism, so as to cause the tub to be substantially drained before the drum is stopped.

As the carriage 59 approaches its right 125 end limit of movement, Fig. 1, the arm or finger 95 will move into the path of the oscillating finger 97, thereby causing the striker 94 to strike the bell 93, as soon as they arrive opposite one another, and sig- 130

nal to the operator that the machine is about to be drained and stopped. By shifting the bell along the slot 91, the point at which the stationary bell is struck by the moving 5 striker can be varied. As the striker moves past the bell, the sound will gradually increase in volume to a maximum, and will then gradually decrease until silenced when the bell is passed. This signaling mechanism can be thrown out of action by taking the screw pin 101 out of the arm 98.

When the carriage 59 is reset for the next washing operation, the ratchet 83 will engage the pawl 84, and rotate the dial 81 15 through the extent of one tooth, so as to indicate the next laundrying operation.

The carriage 59 is driven from the shaft 4 connected with the drum through the mechanism heretofore described, so that this 20 carriage, which constitutes a part of the controlling mechanism, is driven in accordance with the laundrying mechanism, comprising the drum 3 and is, therefore, operable after a predetermined laundrying operation to stop the operation of said laundrying mechanism.

As pointed out above, the mechanism must be adapted to a particular laundry machine, and to the particular speed at 25 which the drum of the laundry machine is operated. In order to provide for this, the adjustable connection between the trunnion and the pawl is provided. By shifting the blocks 73 along the slots 72, in accordance 30 with the revolutions per minute of the drum, as noted on the arm 71, this connecting mechanism is adapted to the speed of the particular washing machine, for it will be obvious that by moving the block 73 to the 35 right, Fig. 7, the oscillation of the arm 70 is increased. By adjustment of the pin 63 in the carriage 59, the interval between the opening of the drain and the stopping of the drum can be varied to suit conditions. 40 Means is, therefore, provided for adjusting the relation between the laundrying and controlling mechanism by the adjustment of the actuating means. The spring 76 is provided for the purpose of preventing break- 45 age, should the timing mechanism stick. This spring forms a connection which will yield.

It will be obvious that various changes 50 may be made in the details without departing from the spirit of this invention. It is, therefore, to be understood that this invention is not to be limited to the specific construction shown and described.

Having thus described the invention, 55 what is claimed is:

1. A controlling device adapted to be attached to a laundrying mechanism having driving mechanism therefor, said device comprising automatic mechanism, adapted to be 60 connected with and operated by said driv-

ing mechanism and operating after a predetermined operation of said laundrying mechanism to definitely stop the operation of said laundrying mechanism, and means for adjusting the connection between said driving mechanism and said automatic mechanism.

2. A controlling device adapted to be attached to a laundrying mechanism having driving mechanism therefor, said device 75 comprising automatic mechanism, adapted to be connected with and operated by said driving mechanism and operating after a predetermined operation of said laundrying mechanism to definitely stop the operation of said laundrying mechanism, means for adjusting said automatic mechanism, and means for adjusting the connection between said driving mechanism and said automatic mechanism.

3. A controlling device adapted to be attached to a laundrying mechanism having driving mechanism therefor, said device comprising automatic mechanism, adapted to be connected with and operated by said driving mechanism and operating after a predetermined operation of said laundrying mechanism to definitely stop the operation of said laundrying mechanism, and means adapted to compensate for different rates 95 of operation of different laundrying mechanisms.

4. A controlling device adapted to be attached to a laundry tub having a drain, and provided with laundrying mechanism having driving mechanism therefor, said device comprising automatic mechanism, adapted to be connected with and operated by said driving mechanism, and operating after a predetermined operation of said laundrying mechanism, adapted to open the drain, and means adapted to compensate for different rates of operation of different laundrying mechanisms.

5. A controlling device adapted to be attached to a laundry tub having a drain, and provided with laundrying mechanism having driving mechanism therefor, said device comprising automatic mechanism, adapted to be connected with and operated by said driving mechanism, and operating after a predetermined operation of said laundrying mechanism, adapted to open the drain, and means for adjusting the connection between said driving mechanism and said automatic mechanism.

6. A controlling device adapted to be attached to a laundry tub having a drain, and provided with laundrying mechanism having driving mechanism therefor, said device 125 comprising automatic mechanism, adapted to be connected with and operated by said driving mechanism, and operating after a predetermined operation of said laundrying mechanism, to open the drain and definitely 130

- stop the operation of said laundrying mechanism, and means adapted to compensate for different rates of operation of different laundrying mechanisms.
- 5 7. A controlling device adapted to be attached to a laundry tub having a drain, and provided with laundrying mechanism having driving mechanism therefor, said device comprising automatic mechanism, adapted 10 to be connected with and operated by said driving mechanism, and operating after a predetermined operation of said laundrying mechanism, to open the drain and definitely stop the operation of said laundrying mechanism after the tub is drained, and means adapted to compensate for different rates of operation of different laundrying mechanisms.
- 15 8. In a machine of the class described, a laundry tub having an outlet, valve mechanism therefor, laundrying mechanism co-operating with said tub, driving mechanism therefor, means for controlling the opera-
- tion of said valve mechanism and of said driving mechanism, adapted to open said outlet and thereafter stop the operation of said laundrying mechanism, and means for adjusting said controlling mechanism to vary the point of opening of said outlet.
9. In a machine of the class described, a laundry tub having an outlet, valve mechanism therefor, laundrying mechanism co-operating with said tub, driving mechanism therefor, means for controlling the operation of said valve mechanism and of said driving mechanism, adapted to open said outlet and thereafter stop the operation of said laundrying mechanism, and means for adjusting said controlling mechanism to vary the time interval between the opening of said outlet and the stopping of the operation of said laundrying mechanism.
- In testimony whereof I affix my signature this 15th day of June, 1917.

THEODORE BIRKENMAIER.
